United States Patent Office.

SAMUEL MARDEN, OF NEWTON, MASSACHUSETTS, ASSIGNOR TO HIMSELF
AND CHARLES PORTER, OF CAMBRIDGE, MASSACHUSETTS.

Letters Patent No. 69,826, dated October 15, 1867.

IMPROVED IMPLEMENT FOR STRAINING BANDS ABOUT BOXES.

The Schedule referred to in these Letters Patent and making part of the same.

TO ALL WHOM IT MAY CONCERN:

Be it known that I, SAMUEL MARDEN, of Newton, in the county of Middlesex, and State of Massachusetts, have invented an improved Implement for Straining Bands or Hoops about Boxes, Bales, &c.; and do hereby declare the following to be a full, clear, and exact description thereof, reference being had to the accompanying drawings, in which—

Figure 1 is a top view,

Figure 2 a front end elevation,

Figure 3 a longitudinal and vertical section, and

Figure 4 a transverse section of the above-mentioned implement.

Figure 5 shows its application to a box.

The object of this invention is to enable the metallic straps or hoops now generally employed for strengthening boxes, bales, &c., to be drawn or strained very tightly about such box and easily held in such strained position until the nails are driven through it which confine it in place.

The invention consists in two clamp-bars or levers, so connected together at or near one end by an encompassing strap or yoke, and turning-pin or fulcrum, as to be readily spread apart to receive the straps between them, and subsequently closed upon such straps with pressure sufficiently powerful to securely hold it between them while it is being strained about the box, the lower lever projecting somewhat beyond the upper, and formed with a curved or rocker-bearing to bear against the edge of the box, and form a powerful leverage to strain the said strap.

In the drawings accompanying this specification, and which illustrate my invention, A denotes a lever having its forward end rounded or formed into a rocker-bearing, *a*, the shape of this bearing being about a quadrant of a circle. A short distance in the rear of this bearing the lever is encompassed by a yoke, *b*, the arms *c c* of which extend upward upon each side of it, and receive between them a clamp-bar, *B*, which is pivoted to such arms *c c* by a horizontal rod or fulcrum, *d*. The lower forward part of the bar *B* is rounded or curved into such a form that it shall recede from the upper surface of the lever *A*, and leave a space between them, when the handle *e* of such bar *B* is raised, and thus allow of the introduction of the metallic hoop or strap between them. The curved surfaces of the lever *A* and bar *B*, as well as the parts immediately in contact with each other, should be covered with a protecting plate of metal, if made of wood, to preserve them from abrasion and injury.

In operating with the above-described implement, the clamp *B* is to be turned upon its fulcrum and raised from contact with the lever *A*, and the hoop or strap to be inserted between the two, as shown in fig. 3 of the drawings. The end of such strap immediately contiguous to the curved ends of the implement is next to be nailed to any proper part of the box, as shown in fig. 5, for instance, and the implement to be slipped along the strap until it passes over the edge of the box, and with the rocker-bearing *a* of lever *A* in contact with its edge, as shown in the said figure. By clasping the handles of the implement, and bringing them towards each other, with a tight grasp, the metallic hoop will be securely held between them. By lowering the two handles and turning the implement with the bearing *a* as a fulcrum or bearing, a very powerful leverage is exerted upon the strap or hoop, and consequently enables it to be strained about the box to any desired extent. As soon as one side of the box has received the strap, the implement is to be slipped along it, until the next corner is reached, and so on in succession until the round of the box is completed.

The utility and practical value of the above-described implement will readily manifest themselves to persons accustomed to hooping boxes or bales.

What I claim and desire to secure by Letters Patent, is—

An implement for hooping boxes, in which the lever *A* and bar *B* are combined with the yoke *c*, substantially in the manner and for the purposes herein shown and described.

SAM'L MARDEN.
